ABSTRACT OF THE DISCLOSURE

A wire rolling mill having a first roll means for treating a wire as it moves in a first direction through the first roll means and a second roll means located adjacent the first roll means for further treating the wire as it moves in a second direction, which is opposed to the first direction, through the second roll means. A wire guide means is situated on the same side of both of the roll means for receiving and guiding the wire as it moves in the first direction from the first roll means and for guiding the wire in the second direction to the second roll means. A stationary deflecting means is operatively connected with this wire guide means to automatically deflect the wire as it moves in the second direction toward the second roll means so that the wire will be reliably received by the latter.

BACKGROUND OF THE INVENTION

The present invention relates to wire rolling mills.

In particular, the present invention relates to that type of wire rolling mill where a wire moves in a first direction through a first roll means which will treat the wire and where the wire then moves in a second direction, which is opposed to the first direction, through a second roll means where the wire is further treated. Thus, after the wire is treated by the first roll means its direction of movement is reversed and the wire is then further treated by the second roll means.

With conventional constructions of this type, considerable difficulty is encountered in switching the wire from the first to the second roll means. Thus, when the direction of movement of the wire is reversed so that it will pass through the second roll means, the wire has to be switched over into alignment with the second roll means to be properly received thereby. For this purpose it is conventional to provide movable chutes or troughs for switching the wire from one to the other of the roll means when the direction of movement of the wire is reversed, and these movable structures include devices such as tilting tables to guide the wire in the rolling mill toward the treating rolls.

In operation, however, such wire guiding structure which includes, for example, movable chutes, have proved to be highly unsatisfactory since it is necessary to provide the structure with a drive, such as a pneumatically operated cylinder, for switching the chute from one path to another path, so that this construction is highly complicated and it is costly to manufacture. Furthermore, faulty operations are frequently encountered with these constructions, and it is inconvenient to lubricate them and to replace worn out parts. In addition, there is a loss in production resulting from the time required to switch such a movable chute.

SUMMARY OF THE INVENTION

It is accordingly a primary object of the present invention to provide a construction which will avoid the above drawbacks.

2

In particular, it is an object of the present invention to provide a structure which not only will reliably direct the wire to the proper roll means but which in addition is composed exclusively of a stationary structure which does not require any drive means and which does not require any maintenance such as lubrication or replacement of parts.

In accordance with the invention the wire guiding structure is used with a wire rolling mill which has a first roll means for treating the wire as it moves in a first direction through the first roll means and a second roll means for further treating the wire as it moves in a second direction, which is opposed to the first direction, through the second roll means. A guide means is provided on the same side of both of the roll means to receive and guide the wire as it moves in the first direction from the first roll means and to guide the wire toward the second roll means as the wire moves in the second direction, and in accordance with the present invention a stationary deflecting means is situated in the path of movement of the wire in the second direction toward the second roll means for deflecting the wire to the second roll means so that the wire will be properly received thereby.

BRIEF DESCRIPTION OF DRAWINGS

The invention is illustrated by way of example in the accompanying drawings which form part of this application and in which:

FIG. 1 is a schematic top plan view of one possible embodiment of a structure according to the present invention;

FIG. 2 is a longitudinal sectional elevation of the structure of FIG. 1; and

FIG. 3 is an elevation of the pair of roll means which treat the wire, FIG. 3 showing the rolls as they appear when seen from the left side of FIGS. 1 and 2.

DESCRIPTION OF THE PREFERRED EMBODIMENT

Referring now to the drawings, the wire rolling mill structure illustrated therein includes a first roll means made up of the lower roll 2 and the right portion of the intermediate roll 3, as viewed in FIG. 3, and a second roll means made up of the left portion of the intermediate roll 3, as viewed in FIG. 3, and the upper roll 5. The rolls 2 and 3 are suitably grooved so as to form the first wire-treating portions 1 and 1' either one of which may be selected for treatment of the wire depending upon the desired treatment by the first roll means. In the same way, the second roll means has grooved portions defining the pair of wire-treating regions 4 and 4' either one of which may be selectively used.

Situated on the same side of both of the roll means, namely the left side, as viewed in FIGS. 1 and 2, is a guide means 6 which receives the wire as it moves in a first direction B from the first roll means into which it advances in the direction of the arrow A shown at the right of FIG. 2, and the guide means 6 also serves to guide the wire in the second direction C, which is opposed to the direction B, as the wire moves along the guide means 6 in this second direction C to the second roll means. As the wire moves in the second direction C along the guide means 6 to the second roll means, a deflecting means 20 of the invention acts automatically to deflect the wire to the second roll means.

The guide means 6 includes a guide chute 9 which is spaced from the pair of roll means. A first feed chute 7 forms a first portion of the guide means and extends between the first roll means and the guide chute 9 for directing the wire from the first roll means to the guide chute 9 of the guide means 6, and it will be noted that the bottom wall 8 of the feed chute 7 is situated at an

elevation higher than the bottom wall of the guide chute 9. In the illustrated example the difference between the elevations of the bottom walls of the feed chute 7 and the guide chute 9 is equal to about twice the diameter of the wire rod 24 which is treated. The bottom walls of the feed chute 7 and the guide chute 9 are integrally connected with each other by the deflecting means 20 which is fixedly connected with both of these bottom walls and which defines a shoulder therebetween, as described in greater detail below.

The guide means 6 includes a second feed chute 10 forming a second portion of the guide means and extending between the guide chute 9 and the second roll means for directing the wire, as it moves in the direction C, from the guide chute 9 to the second roll means. Inasmuch as this second roll means is at an elevation higher than the first roll means, the second feed chute 10 is inclined with respect to the first feed chute 7, but the end of the bottom wall 11 of the second chute 10 which is adjacent the guide chute 9 is situated approximately at the same elevation as the bottom wall of the guide chute 9. However, if desired, this latter end of the bottom wall 11 which is adjacent the guide chute 9 can terminate at an elevation somewhat lower than the elevation of the bottom wall of the guide chute 9.

As was indicated above the second roll means includes the wire-treating portions 4 and 4' either one of which may be selected for treating the wire, and in order to direct the wire to one or the other of these wire-treating portions of the second roll means, the feed chute 10 is pivotally mounted. Thus, the end portion of the bottom wall 11 which is adjacent the guide chute 9 is fixed to a vertically extending pivot pin 12 which extends downwardly through and beyond an opening in a supporting arm or bracket 14 which is fastened to the frame 13 of the machine, and the bottom end of the pivot pin 12 is threaded to receive a nut 18 which can be tightened to fix the feed chute 10 at a selected position. The upper end of the feed chute 10 fixedly carries a pin 15 which extends vertically down through an arcuate slot 17 which extends along a circle whose center is in the axis of the pin 12. This slot 17 is formed in a support member 16 of the machine frame, and the upper surface of member 16 is inclined so as to match the inclination of the bottom wall 11. In the same way, the pin 12 is fixed at its top end to a block which turns on the arm 14 and which has an upper inclined surface fixed directly to the bottom surface of the wall 11 and having the same inclination as the latter. The bottom end of the pin 15 is threaded and carries a nut 19. Thus, the second feed chute 10 can be selectively positioned either in the solid or in the dot-dash line positions indicated in FIG. 1, so that the wire can be selectively directed to one or the other of the wire-treating portions of the second roll means, and when the position of the second feed chute 10 has been selected, the nuts 18 and 19 can be tightened to maintain it in the selected position.

As is apparent from FIG. 1, the deflecting means 20 which is formed by the step or shoulder which is integral with and formed between the bottom walls of the first feed chute 7 and the guide chute 9, is straight and has at its end which is adjacent to the second feed chute 10 a distance from the pair or roll means which is less than the distance between the other end of the deflecting means 20 and the pair of feed roll means, this other end of the deflecting means 20 being situated at the region of the outer side edge of the guide means 6. In one construction of the invention satisfactory results have been achieved by making the inclination of the deflecting means 20 equal to an angle θ with a straight line 21 extending perpendicularly with respect to the directions B and C which is on the order of 50° . Thus, it will be seen that the stationary deflecting means 20 serves to deflect the wire transversely from the first portion of

the guide means formed by the first chute 7 to the second portion of the guide means formed by the second chute 10.

At the end of the guide means 6 which is distant from the roll means, there is a transfer chute 22 where feed rolls 23 and 23' are located. These rolls include the lower idler 23 and an upper driving roll 23', driven from any suitable source, and the upper roll 23' is adjustable in a vertical direction so that the wire 24 after having passed through the first roll means to be treated either at the treating portion 1 or the treating portion 1' thereof will continue to be fed in the direction of the arrow B by the feed rolls 23, 23'.

Thus, during operation the wire 24 will be treated at the first roll means, arriving at the latter in the direction of the arrow A, and after passing through the first roll means the wire moves in the direction B through the guide means 6 to the transfer chute 22 to be received by the feed rolls 23, 23'. After the wire has been treated by the first roll means, the direction of rotation of the feed rolls 23, 23' is reversed so that the wire will not be fed in the opposed direction C, and the leading end of the wire will now be received by the treating portion 4 or the treating portion 4' of the second roll means to be further treated thereby. Transfer or switching of the wire from the first feed chute 7 to the second feed chute 10 is smoothly and automatically brought about by the stationary deflecting means 20.

It is possible for both of the treating portions 1 and 1' to have the same configuration so that one of these treating portions can be used after the other is worn out, and the same is true of the treating portions 4 and 4' of the second roll means. On the other hand, the treating portions 1 and 1' can have different configurations, and the same is true of the treating portions 4 and 4', so that it is possible to select a desired treatment at either one of the roll means.

It is to be noted that the rolls 2, 3, 5 are driven in any suitable way, the intermediate roll 3 being driven by its engagement with the other rolls.

In the solid line position of the chute 10 which is indicated in FIG. 1, this second feed chute 10 will direct the wire 24 to the treating portion 4 of the second roll means, but if desired the chute 10 can be shifted to the dot-dash line position indicated in FIG. 1, so that now the wire will be received by the treating portion 4'.

Thus, with the structure of the present invention the wire is guided from one roll means of the wire rolling mill to the other roll means thereof without requiring any movable chutes or power-operated structure in order to switch the wire from the one to the other roll means. Therefore, the construction is greatly simplified and the cost thereof is reduced while at the same time a source of faulty operation is eliminated and maintenance such as lubrication of parts and replacement of parts is avoided. In addition, any loss of production due to the switching of a movable deflecting structure is eliminated. The inclined deflecting step or shoulder 20 assures a smoothly operating transfer of the wire so that it will be reliably received by the second feed chute 10 to be delivered thereby to the second roll means.

While the structure of the invention has been described in connection with a particular embodiment thereof, it is apparent that improvements and modifications may be made without departing from the scope of the invention as defined in the appended claims.

What is claimed is:

1. In a wire rolling mill, first roll means for treating a wire as it moves in a first direction through said first roll means, second roll means located adjacent but disposed laterally with respect to said first roll means for further treating the wire as it moves in a second direction, opposed to said first direction, through said second roll means, guide means situated on one side of both of said roll means and having a first portion for receiving and guiding the wire as it moves in said first direction

from said first roll means and having a second portion laterally displaced with respect to said first portion for guiding the wire in said second direction to said second roll means, and stationary deflecting means operatively connected with said guide means for automatically deflecting the wire transversely from said first to said second portion of said guide means as it moves in said second direction to said second roll means.

2. In a wire rolling mill, first roll means for treating a wire as it moves in a first direction through said first roll means, second roll means located adjacent said first roll means for further treating the wire as it moves in a second direction, opposed to said first direction, through said second roll means, guide means situated on one side of both of said roll means for receiving and guiding the wire as it moves in said first direction from said first roll means and for guiding the wire in said second direction to said second roll means, and stationary deflecting means operatively connected with said guide means for automatically deflecting the wire as it moves in said second direction to said second roll means, said guide means including an elongated guide chute spaced from both of said roll means, a first feed chute extending between said first roll means and said guide chute and a second feed chute extending between said second roll means and said guide chute, said first feed chute having adjacent said guide chute a bottom wall higher than a bottom wall of said guide chute and said deflecting means interconnecting the bottom walls of said first feed chute and said guide chute and being inclined with respect to said first and second directions for deflecting a wire moving in said second direction away from said first feed chute and into said second feed chute.

3. The combination of claim 2 and wherein said feed chutes are located beside each other and said deflecting means having adjacent said second feed chute an end nearer to said first and second roll means than an op-

posed end of said deflecting means which is distant from said second feed chute.

4. The combination of claim 3 and wherein said deflecting means is substantially straight and makes an angle of approximately 50° with a straight line extending perpendicularly across both of said directions of movement of the wire.

5. The combination of claim 3 and wherein said deflecting means is fixed on the one hand to said guide chute and on the other hand to said first feed chute for fixedly connecting said guide chute and first feed chute to each other.

6. The combination of claim 5 and wherein said deflecting means forms a shoulder situated between said guide chute and first feed chute.

7. The combination of claim 3 and wherein said second roll means has a pair of wire-treating portions, and said second feed chute being pivotally connected to said guide chute for selective movement to locations which will direct the wire in said second direction to one or the other of said wire-treating portions of said second roll means.

8. The combination of claim 3 and wherein said first and second roll means are respectively at different elevations, and said second feed chute being inclined with respect to said first feed chute for directing the wire from the elevation of the first feed chute to the elevation of the second roll means.
